UNITED STATES PATENT OFFICE

157,706

COMBINATION FOOT SCRAPER AND SHOE CLEANER

Annabelle Shaw, Tulsa, Okla.

Application August 23, 1948, Serial No. 148,263

Term of patent 14 years

(Cl. D9—2)

To all whom it may concern:

Be it known that I, Annabelle Shaw, a citizen of the United States, residing at 116 West Fourth Street, Tulsa, county of Tulsa, and State of Oklahoma, have invented a new, original, and ornamental Design for a Foot Scraper and Shoe Cleaner, of which the following is a specification, reference being had to the accompanying drawing, forming part thereof.

I claim:

The ornamental design for a combination foot scraper and shoe cleaner, as shown.

ANNABELLE SHAW.
